UNITED STATES PATENT OFFICE

ROBERT E. WOODSON, OF WEBSTER GROVES, MISSOURI

NUT-SHELL REMOVER

Application filed November 30, 1927. Serial No. 236,619.

This invention relates to machines for separating shell fragments and particles from the kernels of cracked nuts, and maintaining such separation when the nuts are discharged from the machine.

Other objects will appear from the following description, reference being made to the accompanying drawing, in which

Fig. 1 is a side elevation, with parts in section, of my improved machine.

Figs. 2, 3 and 4 are vertical sectional views on the lines 2—2, 3—3 and 4—4, respectively, of Fig. 1.

Fig. 5 is an end elevation of the machine with the end wall of the gear housing removed.

Fig. 6 is an end elevation of the machine showing the driving connections.

My improved machine comprises a frame including a series of rigid supporting legs 1 having a top plate 2 attached to the upper ends thereof, and provided with integral flanges 3 along its sides and ends. The upper ends of the legs 3 project into the corners formed at the intersection of the side and end flanges 3 and are rigidly secured to said flanges. Preferably the legs 1 at the respective ends of the machine are of different heights so that the top plate 2 is supported in an inclined position, inclining downwardly from the feeding-in end to the discharge end of the machine.

At the feeding-in end of the machine a hopper 4 opens into a chute formed by walls 5, 6, 7 and 8 having rigid connection with the top 2 of the machine and with each other. A plate 9 is rigidly supported near the opposite end of the machine and is parallel with the plates 5 and 6 of the feeding-in chute. These plates 5, 6 and 9 support the devices whereby separation of the shell fragments from the edible portions of the nuts is obtained. These devices comprise an upper pair of parallel rollers 10, a pair of side rollers 11, and a pair of lower rollers 12. These rollers are arranged in an annular series and incline downwardly from the feeding-in end to the discharge end of the machine, forming the inclined chute 13 into which the cracked nuts are delivered

from the feed chute. The upper ends of the rollers 10 are rotatively supported by the plate 6 while the upper ends of the rollers 11 and 12 extend to and are rotatively supported by the plate 5 of the feed chute. 55 Thus, the feed chute is in direct communication with the chute 13. The lower ends of all of the rollers 10, 11 and 12 are rotatively supported by the plate 9, the opposite ends of the respective rollers having 60 reduced axial extensions 14 journaled in anti-friction bearings 15 in the said plates 5, 6 and 9. The ends of the rollers from which the extensions 14 project abut against the respective bearing support plates 5, 6 65 and 9, and thus the rollers are held from longitudinal movement and are freely rotatable.

Each of the rollers 10, 11 and 12 is formed with a series of longitudinal parallel grooves 70 or channels 16 extending the full length of the rollers 10 and 11 and terminating at reduced portions 17 at the discharge ends of the rollers 12.

The extension 14 at the lower end of each 75 roller projects through the plate 9 into a gear housing 18, and a gear wheel 19 is attached to each of said extensions 14 in said gear housing. The gear wheels 19 are out of engagement with each other, but all of 80 said gear wheels mesh with a central driving gear 20 rigid on a shaft 21 extending through the removable end wall 22 of the gear housing 18. A pulley 23 is attached to the outer end of the shaft 21 and has operative connection 24 with a pulley 25 driven by a motor 26, shown as supported upon the top plate 2 of the machine. 85

The space between the reduced portions 17 of the rollers 12 is of sufficient area to 90 permit the edible portions of the nuts to pass between the rollers, without being broken, to a discharge chute 27. The spaces between the grooved portions of the rollers forming the chute 13 are not of sufficient 95 area to permit the edible portions of the cracked nuts nor the larger portions of the detached shells to pass between the rollers. The grooves 16, however, form receptacles which receive small shell fragments and 100

particles which are thereby removed from the edible portions of the cracked nuts and discharged into a discharge chute 28.

From the foregoing it will be seen that 5 when the motor 26 is in operation the gear 20 is rotated constantly in one direction and all of the rollers 10, 11 and 12 are rotated constantly in one direction. The cracked nuts entering the roller chute 13 are rapidly 10 agitated and passed toward the discharge chute 27. As a result of the rapid rotation of the rollers 10, 11 and 12 small nut shell fragments are removed, being received in 15 and discharged from the grooves 16, while the larger shell pieces and the edible portions of the nuts pass to the discharge space between the reduced portions 17 of the rollers 12 and into the discharge chute 27. The rollers 10, 11 and 12 are rotated rapidly, desirable results being obtained in some 20 instances by about 500 R. P. M. However, the speed of rotation of the rollers may be varied to obtain the best results determined by observation and for the type of nuts being treated. The rollers 10 are necessary to 25 prevent the nuts from being carried or thrown over the rollers 11 because of the high speed at which it is necessary to rotate these rollers in order to detach the broken shells from the edible portions of the nuts. Moreover, by use of the annular series of 30 rollers including the upper rollers 10 the nuts may be fed through the chute 13 in larger quantities than would otherwise be possible. Thus, the rollers 10 function to 35 permit larger quantities of nuts to be passed through the machine and also positively to prevent the nuts from being thrown or carried over the rollers 11 and also to operate upon the nuts at the top to detach the shell pieces from the edible portions.

The cracked nuts may be delivered into the hopper 4 from any nut cracking machine in use without the necessity of handling the nuts after they pass from the cracking machine.

I do not restrict myself in unessential particulars, but what I claim is:—

1. A machine of the character described 50 comprising an annular series of rollers forming an inclined chute, means for guiding cracked nuts into said chute, and means for rotating all of said rollers in one direction.

2. A machine of the character described 55 comprising an annular series of inclined rollers forming an inclined chute, and each of said rollers having a series of longitudinal grooves in its periphery, means for guiding cracked nuts into said inclined chute, and mechanism for rapidly rotating all of said rollers in one direction.

3. A machine of the character described 60 comprising an annular series of inclined rollers forming an inclined chute, each of said rollers having a series of longitudinal

grooves in its periphery, means for guiding cracked nuts into said inclined chute, mechanism for rapidly rotating all of said rollers in one direction, and chutes for receiving nut shell fragments and the edible portions 70 of the nuts respectively from said inclined chute.

4. A machine of the character described comprising a series of inclined rollers forming an inclined chute and each having a 75 series of longitudinal grooves in its periphery, reduced portions beyond the ends of the grooves on the lower rollers forming a space of sufficient area for the discharge of the edible portions of the nuts between said reduced portions, means for delivering cracked nuts into said inclined chute, and mechanism for rotating all of said rollers in one direction.

5. A machine of the character described 80 comprising a series of inclined rollers forming an inclined chute and each having a series of longitudinal grooves in its periphery, reduced portions beyond the ends of the grooves on the lower rollers forming a space 90 of sufficient area for the discharge of the edible portions of the nuts between said reduced portions, means for delivering cracked nuts into said inclined chute, mechanism for rotating all of said rollers in one direction, 95 a discharge chute for receiving the edible portions of the cracked nuts discharged from between the reduced portions of said rollers, and a discharge chute for the shell fragments.

6. A machine of the character described comprising an annular series of rollers forming a chute, a chute extending downwardly across the ends of a number of said rollers and opening into said first named chute, and 100 means for rotation of all of said rollers in one direction.

7. A machine of the character described comprising a pair of spaced plates, a series 11 of rollers rotatively supported by said plates, an additional plate between said first named plates, a number of rollers rotatively supported by said additional plate and one of said first named plates, all of said rollers forming an annular series of rollers enclosing 11 a chute, and means for delivering cracked nuts into said chute.

8. A machine of the character described comprising an annular series of rollers forming a chute, a number of said rollers being 12 of shorter length than the other rollers and each of said rollers having a series of longitudinal grooves in its periphery, means for guiding cracked nuts into said chute, and means for rotating all of said rollers in one 12 direction.

9. A machine of the character described comprising an annular series of approximately horizontal rollers forming an approximately horizontal chute, the upper roll- 13

ers being of shorter length than the lower rollers, means for guiding cracked nuts beyond the ends of the upper rollers and onto the lower rollers into said chute, and means for rotating all of said rollers in one direction.

10. A machine of the character described comprising an annular series of approximately horizontal rollers forming an approximately horizontal chute, the upper rollers being of shorter length than the lower rollers and each of said rollers having a series of longitudinal grooves in its periphery, means for guiding cracked nuts beyond the ends of the upper rollers and onto the lower rollers into said chute, and means for rotating all of said rollers in one direction.
